COMBINED BACKGUARD AND SHELF FOR
STOVES

Gene H. Cripe and Richard J. Petersen, Los Angeles, Calif., assignors to Utility Appliance Corporation, Los Angeles, Calif., a corporation of California

Application February 4, 1952, Serial No. 18,375

Term of patent 14 years

(Cl. D81—25)

To all whom it may concern:

Be it known that we, Gene H. Cripe and Richard J. Petersen, both citizens of the United States, residing in Los Angeles County, State of California, have invented a new, original, and ornamental Design for a Combined Backguard and Shelf for Stoves, of which the following is a specification, reference being had to the accompanying drawings forming part thereof, in which:

Fig. 1 is a front perspective view of a combined backguard and shelf for stoves, showing our new design with the shelf in raised position;

Fig. 2 is a front elevational view thereof;

Fig. 3 is a top plan view thereof;

Fig. 4 is a side elevational view thereof; and

Fig. 5 is a side elevational view thereof with the shelf in lowered position.

We claim:

The ornamental design for a combined backguard and shelf for stoves, substantially as shown.

GENE H. CRIPE.
RICHARD J. PETERSEN.
